(57) **CLAIM**

The ornamental design for a storage can for oil, as shown and described.

DESCRIPTION

FIG. 1 is a front view of a storage can for oil, according to one embodiment, showing our new design;

FIG. 2 is a left side view thereof;

FIG. 3 is a right side view thereof;

FIG. 4 is a back view thereof;

FIG. 5 is a top view thereof;

FIG. 6 is a bottom view thereof;

FIG. 7 is a front perspective view thereof;

FIG. 8 is right side perspective view thereof;

FIG. 9 is a front view of a storage can for oil, according to embodiment two, showing our new design;

FIG. 10 is a left side view thereof;

FIG. 11 is a right side view thereof;

FIG. 12 is a back view thereof;

FIG. 13 is a top view thereof;

FIG. 14 is a bottom view thereof;

FIG. 15 is a front perspective view thereof; and,

FIG. 16 is a right side perspective view thereof.

The broken lines in the figures illustrate portions of the storage can for oil that form no part of the claimed design.

1 Claim, 16 Drawing Sheets
